UNITED STATES PATENT OFFICE

125,753

DESIGN FOR A MOURNING BADGE OR SIMILAR ARTICLE

Paul Brown, Nyack, N. Y.

Application October 28, 1940, Serial No. 96,141

Term of patent 14 years

To all whom it may concern:

Be it known that I, Paul Brown, a citizen of the United States of America, residing at Nyack, county of Rockland, and State of New York, have invented a new, original, and ornamental Design for a Mourning Badge or Similar Article, of which the following is a specification, reference being had to the accompanying drawing, forming part thereof, wherein:

I claim:

The ornamental design for a mourning badge or similar article, as shown.

PAUL BROWN.
